(57) **CLAIM**

The ornamental design for a caping blade, as shown and described.

DESCRIPTION

FIG. 1 is a perspective side view of a caping blade showing our new design.

FIG. 2 is a top view of the caping blade.

FIG. 3 is a left side view of the caping blade.

FIG. 4 is a back view of the caping blade.

FIG. 5 is a bottom view of the caping blade.

FIG. 6 is a front view of the caping blade.

FIG. 7 is a right side view of the caping blade; and,

FIG. 8 is a perspective side view of the caping blade shown in conjunction with a knife. The broken lines of the blade depict parts of the caping blade that form no part of the claimed design. The broken lines of the knife depict the environment and form no part of the claimed design.
